United States Patent Office

Des. 203,402
Patented Jan. 4, 1966

203,402

CUP

Bjorn Wiinblad, Copenhagen, Denmark, assignor to Rosenthal-Porzellan Aktiengesellschaft, Bavaria, Germany, a corporation of Germany

Filed Oct. 26, 1964, Ser. No. 82,328

Claims priority, application Germany Apr. 25, 1964

Term of patent 14 years

(Cl. D44—9)

I claim:

The ornamental design for a cup, as shown.
